(57) **CLAIM**

The ornamental design for an intravenous priming cap, as shown and described.

DESCRIPTION

FIG. 1 is a front, top perspective view of an intravenous priming cap showing our new design;

FIG. 2 is a right side elevation view of the intravenous priming cap of FIG. 1;

FIG. 3 is a left side elevation view of the intravenous priming cap of FIG. 1;

FIG. 4 is a rear elevation view of the intravenous priming cap of FIG. 1;

FIG. 5 is a front elevation view of the intravenous priming cap of FIG. 1;

FIG. 6 is a top plan view of the intravenous priming cap of FIG. 1; and,

FIG. 7 is a bottom plan view of the intravenous priming cap of FIG. 1.

The dashed lines immediately adjacent to the shaded areas in the figures represent the boundaries of the claimed design. The dashed lines in the figures illustrate the portions of the design that form no part of the claimed design. None of the broken lines form any part of the claimed design.
